CARRYALL

Allen B. Gellman, Glencoe, Ill.

Application March 1, 1956, Serial No. 568,739

12 Claims. (Cl. 132—79)

This invention relates to a cosmetic carrying device and in particular to a new and improved carryall type of cosmetic container.

For purposes such as evening use, women have found highly desirable the use of a modified form of compact wherein additional cosmetics and space for items such as hairpins, loose change, and similar miscellany are provided. Various forms of such cosmetic containers are known in the art, being generally designated "carryall." The carryalls now known in the art, however, have several disadvantages including difficulty of manufacture, with attendant undesirable high cost.

The principal feature of this invention is the provision of a new and improved carryall having simplified construction.

Another feature of the invention is that the carryall is provided with a lipstick container which is removably insertable through an opening in the carryall case, while allowing the cover of the case to remain closed.

A further feature is that the lipstick container is arranged to cooperate with suitable cover latching means to release, when desired, the cover from the closed position.

Still another feature is the provision of a carryall, wherein the latching means comprises a mechanism receivable in the carryall case and aligned automatically with a cooperating latch device carried on the carryall cover by means of the cosmetic holding means.

Yet another feature is that the latch mechanism is provided at one end with a securing means arranged to be locked between the powder holder and the carryall case, and with means for permitting another portion thereof to be yieldably positionable relative to the cover latching device.

Other features and advantages of this invention will be apparent from the following description taken in connection with the accompanying drawings wherein:

Figure 1 is an exploded isometric view of a carryall embodying the invention;

Figure 2 is a top plan view thereof with the cover in an open position;

Figure 3 is a front elevational view thereof with the cover in a closed position;

Figure 4 is an enlarged sectional view thereof taken approximately along the line 4—4 of Figure 3;

Figure 5 is a sectional view thereof taken approximately along the line 5—5 of Figure 4;

Figure 6 is an enlarged elevational view thereof with portions broken away;

Figure 7 is an enlarged fragmentary sectional view thereof showing the latching means in cover-closed position;

Figure 8 is an enlarged fragmentary sectional view thereof, similar to Figure 7, but with the latching means in cover-open relationship; and

Figure 9 is a fragmentary sectional view taken approximately along the line 9—9 of Figure 6.

In the exemplary embodiment of the invention as dis-

2

closed in the drawings, a cosmetic container of the carryall type is shown to comprise a hollow case 10 having a hingedly connected cover 11. Receivably within the carryall is cosmetic holding or compartment means 12 arranged to hold particular cosmetics such as powder or rouge and other small objects such as hairpins and coins. Also carried within case 10 is a cosmetic retaining member comprising a lipstick well 13 which is arranged to extend in alignment with an opening 10a provided in case 10. Means for retaining the well in this position are provided in the form of a yieldable member 14. A lipstick container 15 is adapted to extend through opening 10a and to be removably carried within well 13, with a manual grasping portion 15a extending exteriorly of the case. Cover 11 is provided with a cooperating latching means 16 arranged to secure the cover releasably in the closed position. The releasing of the latching means engagement is effected by manually moving the lipstick container 15 so as to force member 14 and latching means 17 carried thereon inwardly.

Thus, in my carryall is provided a lipstick container readily removable with the cover in the closed position and with the lipstick container also acting as the means for effecting unlatching of the cover when desired. The general structure of the carryall having been described, a more specific description of the elements thereof will now be provided.

Case 10 is provided with a bottom 19b having an upstanding side wall 10c extending peripherally completely around the bottom to form an open-topped container. I have shown case 10 as rectangular, although it should be understood that any other desirable and suitable configuration may be used. Hinge means 18 are provided for pivotally securing cover 11 to the upper end of one portion of sidewall 10c. Hinge means 18 may be of any suitable type being illustratively shown as comprising a plurality of spaced, tubular portions 18a on sidewall 10c, a plurality of complementarily spaced, tubular portions 18b on cover 11 and pintle 18c extending longitudinally through each of said tubular portions. The upper end of sidewall 10c is provided with a laterally inwardly extending flange 10d which extends over the entire periphery of the upper end, except adjacent hinge means 18. Cover 11 comprises a flat plate 11a arranged to extend transversely across the entire open top of case 10 and is provided with a depending peripheral flange 11b arranged to have abutment with sidewall flange 10d when the cover is in the closed position. To effect improved sealing between cover 11 and case 10, an upstanding marginal rim 10c on sidewall flange 10d is provided. This rim abuts the lateral inner surface of cover flange 11b when the cover is in the closed position and thus acts as a movable sealing gasket. If desired, a mirror 11c may be secured to the undersurface of cover plate 11a so as to be viewable when the carryall is open.

Compartment means 12 comprises a pair of containers 12a and 12b each of which may be provided with a suitable cover 12c and 12d, respectively. A connecting plate 12e acts to connect the containers in a spaced relationship. Suitable pivotal mounting means 12f are provided to secure cover 12c to container 12a, and the cover and container together to one edge of plate 12e. Similar pivotal mounting means 12g are provided to secure cover 12d to container 12b, and this cover and container together to an opposite edge of plate 12e. The axes of pivoting of means 12f and 12g are parallel thus allowing parallel positioning of each of the containers relative to each other.

A laterally outwardly extending rim 12h extends peripherally around the upper edge of container 12a, and a similar rim 12i extends around the upper edge of container 12b, rims 12h and 12i acting as abutments for

covers 12c and 12d when they are in their respective closed positions. The spacing of rims 12h and 12i from the bottom of the containers is made comparable or just slightly greater than the spacing between sidewall flange 10d and case bottom 10b, and the positioning of the containers by plate 12e is such as to align the rims 12h and 12i with rim 10e of case 10. Thus, when the containers are forcibly urged into case 10, as seen in Figure 2, rims 12h and 12i snap past and underlie case rim 10e to lock the containers in the case. The dimension of the containers parallel to the pivotal axes is made comparable to the corresponding dimension of case 10 so that they will be locked positionally in this direction also with a relatively narrow space 19 resulting between the containers and the case side wall 10c at the opposite ends of the container by virtue of the extension of rims 12h and 12i into abutment with the side wall.

Compartment means 12 is positioned in case 10 so that the space 12j between containers 12 and 12b is aligned with opening 10a. Lipstick well 13 extends longitudinally through this space and comprises a tubular member having an open end 13a and a closed end 13b. End 13a is flared radially outwardly so that the external diameter thereof is slightly greater than the diameter of opening 10a preventing movement of well 13 outwardly through the opening. An annular groove 13c is provided in the flared end 13a.

Yieldable member 14 comprises a latch element mid-portion 14a having a central hole of a diameter slightly smaller than the external diameter of the flared well end 13a adjacent groove 13c so that member 14 may be secured to the open end of the lipstick well 13 by snapping it into the groove. Latch means 17 is carried on the upper edge of the latch portion 14a for cooperation with latching means 16 on cover 11. In the embodiment being described, latching means 16 and 17 comprise interlocking projections although other suitable means such as pin means may be used. To retain well end 13a against case side wall 10c in alignment with opening 10a, member 14 is further provided with a pair of oppositely extending arms 14b and 14c having at their outer ends securing plates 14d and 14e, respectively. Intermediate the securing plates and mid-portion 14a, the arms are provided with bosses 14f and 14g, respectively. The height of the bosses and the thickness of the arm additively approximate the spacing between the containers and side wall 10c so that the arms are held against lateral movement across space 19. The height of plates 14d and 14e is made comparable to the spacing of container rims 12h and 12i from the bottom of the containers so that when member 14 is inserted into case 10, as seen in Figures 4 and 6, it is held against movement transversely between the container rims and the case bottom 10b. A pair of inwardly projecting ears 14h and 14i extend from latch portion 14a to abut the inner walls of the containers 12a and 12b and position member 14 in alignment with opening 10a.

Lipstick container 15 may be of the conventional tubular construction, having an external diameter comparable to the internal diameter of well 13 whereby it may be inserted through opening 10a and frictionally held in well 13. Grasping portion 15a is diametrically enlarged to form a shoulder 15b which is diametrically smaller than opening 10a, but larger than the internal diameter of well end 13a. Thus, when container 15 is fully inserted into well 13, further inward movement of the container, by virtue of abutment between shoulder 15b and cap end 13a, moves well 13 inwardly carrying with it mid-portion 14a so as to disengage latching means 17 from cover latching means 16. The inward movement of mid-portion 14a is effected pivotally about bosses 14f and 14g. At its outer end grasping portion 15a is radially enlarged to form a stud shoulder 15c. This shoulder provides a positive abutment with case sidewall 10c around opening 10a to limit the insertion of lipstick con-

tainer into case 10 and prevent overstressing of yieldable member 14.

The assembly and disassembly of my compact is extremely simple. Yieldable member 14 is slid over the inner end of lipstick well 13 until it snaps into groove 13c. This assembly, as best seen in Figure 1, is then positioned in case 10 with well open end 13a adjacent and the well in general alignment with opening 10a, as best seen in Figure 4. Compartment means 12 is snapped into place in case 10 by pressing rims 12h and 12i of containers 12a and 12b, respectively, under the case rim 10c. The pivotal connection to plate 12e allows the containers to be urged individually into place. Ears 14h and 14i on the yieldable member 14 slidably abut the containers as they are inserted and position the yieldable member 14 in accurate alignment with the opening 10a. When compartment means 12 is fully inserted and locked in case 10, as best seen in Figure 6, securing plates 14d and 14e of yieldable member 14 are locked in place in space 20 between means 12 and case side wall 10c. Lipstick container 15 may now be inserted through opening 10a into its well 13 which is now held in alignment with the opening 10a.

Whenever the use of the lipstick alone is desired, container 15 may be withdrawn from case 10 by the grasping of portion 15a and moving of the container longitudinally outwardly from well 13 without effecting the positioning of latching means 17. When it is desired to open the compact, lipstick container 15 is urged inwardly through opening 10a so that shoulder 15b on container 15 abuts cap end 13a and urges the cap and latching means 14 inwardly. This movement of latching means 14 effects a separation thereof from latching means 16 on cover 11, and the cover may be pivoted to the open position, as seen in Fig. 1, allowing access to the cosmetic retaining, compartment means 12 held in case 10.

While I have shown and described certain embodiments of my invention, it is to be understood that it is capable of many modifications. Changes, therefore, in the construction and arrangement may be made without departing from the spirit and scope of the invention as defined in the appended claims.

I claim:

1. A carryall comprising: a hollow case having an open top with a cover openably thereacross, and a wall portion defining an opening into the case; means for latching said cover in closed position across said case top; a tubular cosmetic retaining means removably extending through said opening and into said case and having manual grasping means projecting exteriorly of said case; and means operably associated with said cosmetic retaining means for releasing the latching means by manipulation of said grasping means in one manner and allowing the removal of the cosmetic retaining means without release of the latching means by manipulation of said grasping means in a second manner.

2. A carryall comprising: a hollow case having an open top with a cover openably thereacross, and a wall portion defining an opening into the case; means releasably latching said cover in closed position across said case top; cosmetic retaining means retained in said case; a well in said case and having a hollow in communication with said opening; and a tubular lipstick container removably extending through said opening and into said hollow and having manual grasping means projecting exteriorly of said case, said well being operably associated with said lipstick container to effect release of the latching means by manipulation of said grasping means in one manner and allowing the removal of the cosmetic retaining means without release of the latching means by manipulation of said grasping means in a second manner.

3. In a cosmetic carrying device having a case with an openable cover and yieldable means in the case for latching the cover in a closed position, means for releas-

ing the latching means comprising a tubular lipstick container having one end removably extended through the case, a first shoulder on said container arranged to abut the latching means and effect release thereof, and a second shoulder on the outer end of the container arranged to abut the case and preclude complete insertion of the container into the case.

4. A carryall comprising: a hollow case having a bottom, and an upstanding sidewall terminating in an open top with a peripheral flange extending laterally inwardly; a cover pivotally secured to said case to abut said flange in a closed position wherein said cover extends across said open top, said cover having latch means; a cosmetic container having means for retention thereof in said case comprising a margin removably snapped under said flange; and a spring latch member having a securing portion locked between said container and said sidewall and between said flange and said bottom, and cooperating latch means thereon having releasable engagement with said cover latch means.

5. A carryall comprising: a hollow case having a bottom, and an upstanding sidewall having an opening and terminating in an open top with a peripheral flange extending laterally inwardly; a cover pivotally secured to said case to abut said flange in a closed position wherein said cover extends across said open top, said cover having latch means; a container having means for retention thereof in said case comprising a margin removably snapped under said flange; a spring latch member having a securing portion locked between said container and said sidewall and between said flange and said bottom, and cooperating latch means thereon having releasable engagement with said cover latch means; and means for moving said last-named latch means when desired including a member fully received in said case and connected to said spring latch member to be adjacent said sidewall opening, and a member extending removably through said sidewall opening and engaging said last-named member to effect movement thereof and move thereby the latch means on said spring latch means.

6. A carryall comprising: a hollow case having a bottom, and an upstanding sidewall terminating in an open top with a peripheral flange extending laterally inwardly; a cover arranged to abut said flange in a closed position wherein said cover extends across said open top; compartment means comprising a pair of containers, a connecting plate having a pair of opposite edges, and means securing one container to the plate at one edge and the other container at the other edge to pivot about mutually parallel axes, and each of said containers having means effecting retention thereof in said case comprising a margin removably snapped under said flange.

7. A carryall comprising: a hollow case having a bottom, an upstanding sidewall having an opening and terminating in an open top with a peripheral flange extending laterally inwardly; a cover pivotally secured to said case and abutting said flange in a closed position wherein said cover extends across said open top, said cover having latch means; compartment means comprising a pair of containers, a connecting plate having a pair of opposite edges, and means securing one container to the plate at one edge and the other container at the other edge to pivot about mutually parallel axes, each of said containers being spaced apart by said plate to abut an opposite portion of said sidewall laterally of said opening, thereby to fix the lateral positioning of said containers in said case, each of said containers further having means retaining said compartment means in said case comprising a margin removably snapped under said flange; a spring latch member having a securing portion locked between said container and said sidewall and between said flange and said bottom, ears projecting

inwardly between and abutting said containers to position said latch member laterally of said opening, and cooperating latch means movably adjacent said cover latch means; and means for moving said last-named

5 latch means when desired including a member fully received in said case between said containers and connected to said spring latch member to be adjacent said sidewall opening, and an element projecting through said opening and removably, frictionally held in the last-named member and arranged to transfer movement thereto to move thereby said last-named latch means.

8. The carryall of claim 7 wherein said last-named member comprises a lipstick well and said element comprises a lipstick container having a shoulder abutting the well limiting movement of the container into the well.

9. The carryall of claim 7 wherein said last-named member comprises a lipstick well and said element comprises a lipstick container having a first shoulder abutting the well limiting movement of the container into the well, and a second shoulder arranged outwardly of said first shoulder abutting the sidewall portion defining said opening limiting insertion of the container into the case.

10. In a carryall having a hollow case and a cover, 25 means for releasably latching said cover closed, comprising: latch means carried on the cover; cooperating latch means received in the case and having a yieldable bar, a projection on said bar intermediate the ends thereof providing a pivot point, a securing element at one end of 30 said bar fixedly secured relative to the case, and a latch element at the other end of the bar normally positioned in a latched position for engagement with the first-named latching means; and means removably passed through the case to pivot said other bar end about the projection and 35 move said latch element from latched position.

11. In a carryall having a hollow case and a cover, means for releasably latching said cover closed, comprising: latch means carried on the cover; cooperating latch means received in the case and having a pair of oppositely extending yieldable bars, each of said bars having a projection intermediate the ends thereof providing a pivot point therefor, a securing element at one end of each of said bars fixedly secured relative to the case, and a latch element interconnecting the other end of the bars 45 and normally positioned in a latched position for engagement with the first-named latching means; and means removably passed through the case to pivot said other bar ends about the projection and move said latch element from latched position.

12. In a carryall having a hollow case and a cover, means for releasably latching said cover closed, comprising: latch means carried on the cover; cooperating latch means received in the case and having a pair of oppositely extending yieldable bars, each of said bars having a projection providing a pivot point therefor, a securing element at one end of each of said bars fixedly secured relative to the case, and a latch element interconnecting the other end of the bars and normally positioned in a latched position for engagement with the first-named latching means, said latch element having a hole therethrough; and means removably passed through the case and said hole, and having shoulder means releasably engaging the latch element to pivot said other bar ends and move said latch element from latched position.
